UNITED STATES PATENT OFFICE

LARRY VENDITTI, OF PHILADELPHIA, PENNSYLVANIA

DESIGN FOR AN AQUARIUM

Application filed July 14, 1930. Serial No. 36,347. Term of patent 14 years.

To all whom it may concern:

Be it known that I, LARRY VENDITTI, a citizen of the United States, residing at Philadelphia, in the county of Philadelphia and Commonwealth of Pennsylvania, have invented a new, original, and ornamental Design for an Aquarium, of which the following is a specification, reference being had to the accompanying drawing forming a part thereof.

Figure 1 is a view of the aquarium in front elevation,

Figure 2 is a top plan view of the aquarium, and

Figure 3 is a view of the aquarium in end elevation.

I claim:

The ornamental design for an aquarium, as shown.

LARRY VENDITTI.
